UNITED STATES PATENT OFFICE.

JEFFREY T. FERRES, OF LOS ANGELES, CALIFORNIA.

TENSION MECHANISM FOR PAPER-ROLLS, &c.

1,270,279.

Specification of Letters Patent. Patented June 25, 1918.

Application filed January 15, 1916. Serial No. 72,256.

To all whom it may concern:

Be it known that I, JEFFREY T. FERRES, a citizen of the United States, residing at Los Angeles, Los Angeles county, California, have invented certain new and useful Improvements in Tension Mechanism for Paper-Rolls, &c., of which the following is a specification.

My invention relates to tension mechanism for rolls of paper or other material which is wound in roll form or on reels and drawn therefrom by the machine which utilizes or manipulates the paper or other material whatever it may be. The principal object of my invention is to provide simple and efficient tension mechanism for automatically applying tension to the roll in proportion to the diameter and weight of material in the roll. At the beginning when the roll is at its greatest diameter and heaviest weight the sheet as it is being withdrawn from the roll has the greatest amount of leverage because of the large diameter of the roll and consequently the greatest amount of tension may be applied to the roll. However, as the sheet or other material is consumed and the diameter of the roll therefore decreases, the leverage of the sheet correspondingly decreases and the tension should be correspondingly relieved. My invention provides a mechanism for meeting these conditions with the result that such mechanism automatically applies tension to the roll in proportion to the weight and diameter thereof, with the result that the tension on the sheet automatically remains the same whether the roll is large or small in diameter.

Another object of my invention is to provide simple and efficient means for adjusting the entire tension mechanism and the roll on the main frame so as to bring the sheet in alinement with the machine for proper working purposes. Still another object of my invention is to provide simple and efficient means for securing the roll to its shaft and also to accommodate different lengths of roll.

In the drawings Figure 1 is a plan view of my tension mechanism showing the roll of material in dotted lines; Fig. 2 a section on the line 2—2 of Fig. 1 but on a larger scale; Fig. 3 a section on the line 3—3 of Fig. 2; Fig. 4 a section on the line 4—4 of Fig. 1, but on a larger scale; Figs. 5 and 6 sectional elevations on the lines 5—5 and 6—6,

respectively of Fig. 1, but on a larger scale; Fig. 7 a plan view of the parts shown in Fig. 6 but with the roll removed; Fig. 8 a section on the line 8—8 of Fig. 5; and Fig. 9 a section on the line 9—9 of Fig. 5.

While my invention may partake of different forms or embodiments, I have shown herein a comparatively simple, efficient and practical construction for the purpose and I will now proceed to describe the same without intention of limiting myself to details of construction except as may be required by specific claims. Moreover, while my invention has been primarily designed and adapted to rolls of paper it will be understood that my invention is not limited to this particular use but that it may be applied to rolls or reels of any material. However, for the sake of convenience I will refer to the roll as a paper roll and consequently the material withdrawn from there as a sheet of paper.

As shown in Fig. 1, the paper roll A illustrated by the dotted lines is supported upon a rotatable shaft 1, supported at its opposite ends in bearings open at their upper ends so that the shaft may be readily removed for the purpose of replacement and the insertion of a fresh roll. One of the bearings 2 is supported in any suitable manner, as by means of a part of a main frame 3 while the other bearing 4 is in the form of a yoke whose manner of mounting will be hereinafter described in detail. The roll shaft is provided with two adjustable heads 5 and 6 movable against ends of the roll for clamping or binding the same onto the shaft. The head 5 gives a large adjustment whereas the head 6 gives the fine adjustment.

Referring to the head 5 the same is provided with a tapered sleeve portion 5^a which engages the center opening of the roll. The body of this head is provided with a spring-pressed plunger 7 adapted to engage in any one of a series of holes 8 spaced apart and extending longitudinally of the shaft. By withdrawing the plunger the head 5 may be moved to any position on the shaft and held thereat by the engagement of the plunger 7 with the particular hole 8 by which the head has been adjusted.

Referring to the other head 6, the same comprises a circular collar portion and a sleeve portion 6^a extending inwardly and engaging the central opening in the roll. This end of the shaft on which the head 6

is mounted is screw-threaded and provided with the longitudinal key-way 1^a adapted to receive a key 9 which is held within the inner wall of the sleeve extension 6^a by 5 means of the screw 10. This collar is therefore capable of being moved or adjusted longitudinally of the shaft. For this purpose this head or collar 6 is operatively connected with a rotatable sleeve 11, screw- 10 threaded onto the shaft 1 and having a hand wheel 12 for rotation purposes. This sleeve is provided with a circumferential flange 13, fitting within the collar 6 and having a peripheral groove 13^a to accommodate the inner ends of a series of round end screws 14. A ball bearing 15 is interposed between the collar 6 and the flange 13. When the sleeve 11 is rotated in the proper direction the collar will be moved inwardly against the 15 roll until it is clamped sufficiently between the collars 5 and 6.

It will be understood that a larger adjustment is obtained by the clamping head 5 which is moved to the hole 8 nearest to 25 the desired position of adjustment, after which the final adjustment is obtained in the manner explained by means of the other head.

The bearing 4 of the roll shaft is in the 30 form of a yoke as shown in Fig. 6 and provided with a downwardly extending stem 16 movable in and guided by a vertical opening in a bracket 17. This bearing is upwardly spring-pressed by means of a spring 35 18 in said opening bearing at one end against the stem 16 and at its other end against the inner end of a rotatable adjusting screw 19 screwing into the lower end of the bracket with the result that the tension 40 of the spring may be increased or decreased causing this bearing to carry a less or greater amount of the weight of the roll as desired. As a matter of fact, two rolls of paper weighing the same and of the same 45 diameter, but differing in the thickness of the paper of which they consist, require different degrees of tension on account of the difference in thickness of the paper. This is accomplished, as above stated, by 50 carrying part of the weight of the rolls on the bearing 4, screwing up of the screw 19 reducing the friction as hereinafter explained.

By preference and for the purpose of 55 bodily adjusting longitudinally the entire roll of paper and its shaft, with respect to the main frame 3 of the machine, this bracket 17 is made separate from such frame and constructed in such a way as to slide 60 horizontally with respect thereto. As shown in Figs. 5, 6 and 8, this bracket is dovetailed into one end of the main frame. In order that the necessary machine work may be done on separate small parts instead of 65 a large part such as the main frame I pro-

vide a removable plate 20 secured to the main frame by means of two slide plates 21 secured to the main frame by means of bolts 22. These plates 21 are of course undercut to provide for the dove-tail slide 70 and are adapted to receive the dovetailed slide portion 17^a of the bracket 17. This bracket has on its dove-tailed portion an inwardly extending flange 17^b, Fig. 8, provided with an opening 17^c through which 75 passes an adjusting screw 23, the latter being held against removal by means of the set screw 24 engaging a peripheral groove 23^a in such screw. This adjusting screw screws into a flange 20^a of the plate 80 20 with the result that as the hand-wheel 24^a of the adjusting screw is rotated the bracket and all parts supported thereby are adjusted horizontally with respect to the main frame 3.

Referring further to the tension mechanism the same comprises, as herein shown, a pair of pivoted shoes 25 adapted to engage the bottom edge and also two opposite edges of a friction wheel or drum 26 secured to 90 one end of the roll shaft 1, at a point beyond its yoke bearing 4. These shoes are pivoted intermediate their ends on pivot pins 27 mounted in horizontal openings in oppositely extending arms 17^d of the bracket 95 17. By preference each of these shoes presents to the wheel or drum two separate friction surfaces, one at each end thereof to provide friction simultaneously at the bottom edge and a side edge of the wheel. 100 However, by preference these shoes do not immediately contact such wheel but a friction lining 28 of leather or other suitable material is applied to the inner faces of these shoes.

In practice the weight of the roll is not permitted to rest, to any considerable extent upon the yoke bearing 4, but mostly upon the friction lining 28 at the lower ends of the shoes. Inasmuch as these shoes are pivoted at points intermediate their length it follows that the upper ends of these shoes are braced against opposite sides of the wheel 26 with a pressure corresponding in amount to the weight of the roll. If, then, weak paper is being run, the screw 19 is operated to yieldingly press the yoke bearing 4, which is relatively free-running, upwardly, thus relieving to some extent the frictional or braking effect of the shoes 25, while if a heavier strong paper is being used the screw may need to be operated to lower the yoke and thus increase the friction and consequent tension on the sheet. Obviously as the sheet of paper or other material is fed off from the roll and the roll gets lighter the upward stress of the spring 18 tending to lift the yoke against the free running shaft 1 will relieve the shoes of an amount of pressure determined by the ad- 110 115 120 125 130

justment of the spring, and the remaining pressure, carried by the shoes, will gradually be reduced as the roll becomes smaller and lighter. Therefore, as the roll gets 5 smaller the frictional effect of the shoes and tension on the sheet of paper is decreased in proportion. The spring connection between the screw and yoke permits the weight of the roll, which in all cases is supported 10 largely by the shoes, to act freely upon them, so that the compensating effect of the diminishing weight of the roll as it gets smaller is fully realized. As a result of the adjustment of the yoke 4 and the compensating effect of the varying diameter and 15 weight of the roll, there is no danger of tearing the paper or other material as would be the case if the same amount of tension were applied to the roll from beginning to 20 end.

When the first roll of a new lot of paper is being applied the adjusting screw 19 is adjusted so as to take the necessary amount of the weight of the roll, as different papers 25 require different degrees of tension according to their thickness and strength. The lower ends of the shoes are limited in their extreme downward movement by means of stop pins 29 on the sides of the bracket 17. 30 In order to provide for adjustment of the shoes inwardly in order to take up any wear of the friction lining 28 these pivot pins 27 are pivoted with an eccentric portion 27^a received within the arms 17^a with the result 35 that when the pins are slightly turned by applying a wrench to the angular portion 27^b the shoe is moved inwardly toward the friction wheel 26. The pin is clamped in its adjusted position by means of the nut 30 40 and washer 31 and such pin is held against endwise removal by means of the set screw 32 in each shoe and engaging a peripheral groove 27^c therein.

I claim:

45 1. In combination with a roll and its shaft, a friction wheel thereon, tension mechanism including a pivoted shoe supporting such wheel and also bearing constantly thereagainst with a pressure proportionate 50 to the weight of the roll.

2. In combination with a roll and its shaft, a friction wheel thereon, tension mechanism including a pivoted shoe in the form of a lever one of whose arms supports such 55 wheel, and the other of whose arms bears constantly against the member with a pressure proportionate to the weight of the roll.

3. In combination with a roll and its shaft, a friction wheel thereon, tension mechanism 60 including a pair of pivoted shoes in the form of levers whose similar adjacent arms support such wheel and whose other arms bear constantly against opposite sides of said wheel with a pressure proportionate 65 to the weight of the roll.

4. In combination with a roll and its shaft, a friction wheel thereon, a pair of pivoted shoes in the form of levers whose similar arms support and apply friction to the bottom of the wheel and whose other arms 70 are movable against opposite sides of said wheel with a pressure proportionate to the weight of the roll.

5. In combination with a roll and its shaft 75 a friction wheel thereon, a pair of pivoted shoes in the form of levers whose similar arms support and apply friction to the bottom of the wheel and whose other arms are movable against opposite sides of said wheel with a pressure proportionate to the 80 weight of the roll, and a withdrawable bearing for supporting the shaft when the said wheel is not supported by the shoes.

6. In combination with a roll and its shaft, 85 a friction wheel thereon, a pair of pivoted shoes in the form of levers whose similar arms support and apply friction to the bottom of the wheel and whose other arms are movable against opposite sides of said wheel with a pressure proportionate to the weight 90 of the roll, and an adjustable spring pressed bearing for supporting the shaft when said wheel is not supported by the shoes.

7. In combination with a roll and its shaft, 95 a friction wheel thereon, a pair of pivoted shoes in the form of levers whose similar arms support and apply friction to the bottom of the wheel and whose other arms are movable against opposite sides of said wheel with a pressure proportionate to the weight 100 of the roll, a bracket having oppositely extending arms in which the shoes are pivoted, and a withdrawable bearing mounted in the bracket for supporting the shaft when said wheel is not supported by the shoes.

8. In combination with a roll and its shaft, 110 a friction wheel thereon, a pair of pivoted shoes in the form of levers whose similar arms support and apply friction to the bottom of the wheel and whose other arms are movable against opposite sides of said wheel with a pressure proportionate to the weight 115 of the roll, a bracket having oppositely extending arms in which the shoes are pivoted, and having a bearing for the shaft including a yoke having a stem movable in the bracket, a spring bearing against such stem, and an adjusting screw co-operating with the spring.

9. In combination with a roll and its shaft, 120 a friction wheel thereon, a pair of pivoted shoes in the form of levers whose similar arms support and apply friction to the bottom of the wheel and whose other arms are movable against opposite sides of said 125 wheel with a pressure proportionate to the weight of the roll, and means whereby the shoes may be adjusted toward and away from the wheel.

10. In combination with a roll and its 130

- shaft, a friction wheel thereon, a pair of pivoted shoes in the form of levers whose similar arms support and apply friction to the bottom of the wheel and whose other arms are movable against opposite sides of said wheel with a pressure proportionate to the weight of the roll, and eccentric pivot pins for the shoes which pins are adjustable rotarily to adjust the shoes toward and away from the wheel.
11. In combination with a roll, a main frame, a removable plate thereon, dovetail slides secured to the frame and holding said plate in position, a bracket having a portion coöperating with said slides and arranged to move horizontally on the frame, and tension mechanism supported on the bracket and coöperating with the roll to provide tension therefor.
12. In combination with a roll and its shaft, a friction wheel secured to said shaft, tension mechanism including a pair of pivoted shoes arranged to support said wheel and also bearing constantly thereagainst with a pressure proportionate to the weight of the roll, and a relatively free-running, adjustable bearing coöperating with the roll

for supporting a predetermined amount of the weight thereof.

13. In combination with a roll provided with a shaft, a free-running bearing in the form of a yoke engaging said shaft, adjustable and elastic means for pressing the yoke upward to support a predetermined part of the weight of the roll, and frictional bearing members arranged to support the remaining portion of the weight of the roll and supply friction proportionate to such remaining portion of the weight.

14. In combination with a roll provided with a shaft, a free-running bearing having a vertical stem, spring tension tending to lift said stem, adjusting means for varying the tension of the spring to lift a predetermined portion of the weight of the roll, and a pair of rocking friction shoes arranged to support the remaining portion of the weight of the roll and supply friction proportionate to such remaining portion of the weight.
